[57] CLAIM

The ornamental design for a self-contained earset communication device, shown and described.

DESCRIPTION

FIG. 1 is a perspective view of a self-contained earset communication device showing my new design;
FIG. 2 is a top plan view thereof;
FIG. 3 is a bottom plan view thereof;
FIG. 4 is a right side elevational view thereof;
FIG. 5 is a left side elevational view thereof;
FIG. 6 is a rear elevational view thereof; and,
FIG. 7 is a front elevational view thereof.
The broken line(s) which define the bounds of the claimed design form no part thereof.
